UNITED STATES PATENT OFFICE.

CARL GIESER AND GLENN SHAFFER, OF DES MOINES, IOWA; SAID SHAFFER
ASSIGNOR TO SAID GIESER.

VALVE-GRINDING TOOL.

1,346,785.

Specification of Letters Patent.

Patented July 13, 1920.

Application filed February 4, 1920. Serial No. 356,340.

To all whom it may concern:

Be it known that we, CARL GIESER and GLENN SHAFFER, citizens of the United States, and residents of Des Moines, in the 5 county of Polk and State of Iowa, have invented a certain new and useful Valve-Grinding Tool, of which the following is a specification.

An object of our invention is to provide a 10 valve grinding tool of simple, durable and inexpensive construction, which is so designed that it is not necessary to remove the valve casing, when it is desired to grind the movable valve closure member.

More particularly it is our object to provide a valve grinding tool, having gripping members on its lower end, that are adapted to grip and engage a movable valve closure member, whereby rotation of the tool will 15 cause the valve member to rotate in its seat and thus cause it to be ground.

Still a further object is to provide a tool that can be adjusted, so as to fit movable valve closure members of various sizes, the 20 tool being provided with a handle or wrench engaging portion at its upper end, whereby it may be easily rotated.

Still another object is to provide a centering device, which is slidably mounted 25 upon the tool for use, when large valves are being ground, the centering device being provided with locking means, for absolutely locking it to the valve casing.

Still a further object is to provide gripping fingers on the tool, which are adjustable to various sizes, and adapted to engage the movable valve member in the portion, which is designed to be secured to the valve 30 stem.

With these and other objects in view, our invention consists in the construction, arrangement and combination of the various parts of the device, whereby the objects contemplated are attained, as hereinafter more 35 fully set forth, pointed out in our claims, and illustrated in the accompanying drawings, in which:

Figure 1 shows a side elevation of our device with the centering device attached 40 thereon, parts being broken away and shown in section, in order to better illustrate the construction.

Fig. 2 shows a view of the gripping fingers attached to the movable valve member, 45 the centering device being omitted.

Fig. 3 shows an enlarged, detail view of the gripping fingers, the dotted lines showing one of the adjusted positions of the fingers.

Fig. 4 shows a view of the gripping fingers in engagement with the movable valve member; and

Fig. 5 shows a central, sectional view taken on line 5—5 of Fig. 1.

In the accompanying drawings, we have 60 used the reference numeral 10 to indicate the ordinary valve casing, which is provided with a valve seat 11 and a movable valve closure member 12.

Secured to the valve casing 10 are the 70 pipes 13 and 14. The movable valve closure member 12 is provided with an annular screw-threaded recess 15.

The ordinary valve stem for opening and closing the valve member 12 is designed to 75 be secured in the screw-threaded portion of the recess 15.

It will be understood that the valve here- 80 fore described is of the ordinary common kind, and that our device is adapted to grind the valve member 12 in its seat 11, so as to make an absolutely perfect tight joint.

When it is desired to grind the valve member 12, the valve stem is taken out and our tool is then attached in its place. Our 85 tool consists of a casing 16, which is provided intermediate of its ends with opposite registering openings 17. The casing 16 is provided at its upper end with a squared portion 18, which is designed to receive a 90 handle or the like 19.

It will be understood that the handle 19 is detachable, and a wrench or ordinary brace may be used for causing the casing 95 member 16 to rotate.

At the lower end of the casing 16, we provide gripping fingers 20. The gripping fingers 20 are pivoted to the lower end of the casing 16, by means of the pins 21.

The lower end of each of the fingers 20 100 is pivoted at 21. The outer lower side of each of the fingers 20 is provided with a knurled portion 22. The knurled portion 22 is designed to engage the screw-threaded portion of the recess 15.

In order to cause the fingers 20 to engage and firmly hold the valve member 12, we have provided a rod 23, which has a screw-threaded portion 24 near its upper end.

Mounted on the screw-threaded portion 24 110

of the rod 23 is the nut 25. The nut 25 is adapted to have its sides extend out through the opposite registering openings 17.

The lower end of the rod 23 extends below the lower edge of the casing 16 and is provided with a screw-threaded portion 26. Fixed on the screw-threaded portion 26 of the rod 23 is the nut 27. The nut 27 is cone-shaped, and is adapted to have its sides 10 rest adjacent to the beveled surface 21 of the fingers 20, when it is in its lowermost position.

From the construction of the parts heretofore described, it will be seen that by rotating the nut 25, it will cause the rod 23 to be vertically adjusted and thus cause the nut 27 to extend the fingers outwardly on their pivots.

It will be seen that we can adjust our 20 fingers to the various positions, whereby various sizes of movable valve closure members may be taken care of.

In order to use our device on small valves, we remove the nut 27 from the lower end, 25 and by moving the rod 23 into its uppermost position, we are then able to move the fingers 20 close together, so that real small valves may be ground. This is shown in Fig. 2 of the drawings; the nut 27 being removed and the screw-threaded portion 26 being plainly shown.

When we use our device on large valve members, it is then necessary to have some 35 sort of a bearing or centering device to insure the operator that the valve is being ground absolutely accurate.

In order to accomplish this, we have provided a centering device A, which comprises a cone-shaped member 28, which has a hub 40 29. The hub 29 is designed to rest adjacent to the casing 16.

From the construction just described, it will be seen that the centering device is 45 slidably mounted on the casing 16, and can readily be removed when the use of it is not needed; that is when the tool is being used on small work.

When the centering device A is used, it is necessary to lock it to the valve 10. In 50 order to accomplish this, we have provided the bars 30, which are provided with slots 31. A machine bolt 32 extends through the slot 31 and extends into the cone-shaped member 28. The cone-shaped member or 55 centering device just described is designed to be received in the opening of the valve stem.

On the lower ends of the rods 30, we provide the set screws 33, which can be tightened or loosened, as desired.

When the valve stem opening of the valve casing 10 is large, the centering device A will be received farther into the valve casing 10, and therefor it is necessary to ad-

just the position of the bars 30, so that the 65 set screws 33, when tightened will rest against the rim or upper edge of the opening in the valve casing 10.

When it is desired to adjust the bar 30, the machine bolt 32 is loosened and the bar 70 30 is then moved to any desired position and is locked by the machine bolt 32. The bar 30 is received in a recess in the cone-shaped member 28 and this prevents any pivotal movement, and permits only vertical movement 75 of the bar 30.

By providing the centering device A, it enables the tool to be placed in the valve, and to be held absolutely vertical, so that during the grinding of the valve, it will be 80 held in such position, that when the valve stem is again placed in the valve, the movable valve member will fit absolutely accurate with the valve seat 11.

In order to rotate the tool, at a high rate 85 of speed, the handle member 19 is removed and an ordinary brace is placed over the squared portion 18, and then by rotating the brace the tool will be operated, and thus cause the valve to be ground into position. 90

Some of the advantages of our device are 95 that we are able to grind the valve seat with the movable valve member and thus when they are ground together, the joint will be more accurate than could be possibly made, if some independent tool is used.

Another advantage of our tool is that 100 we are able to grind the valve seat without removing the valve casing from its pipe connections. It will be understood that this saves a great deal of labor and time, and it is very important sometimes to have the valve seat perfectly, and yet it would be a serious handicap, if it were necessary to remove the valve casing from its operative 105 position, in order to have it ground each time.

Another advantage of our device is that 110 it is adjustable, so that it may operate in various sizes of valves, and when it is operated in a large type of valve, we have provided a centering device, which will tend to cause the tool to be vertical relative to the valve seat, and thus causes our tool to work much more efficiently, since we have 115 something to steady and hold the tool in proper position. After the valves have been ground, the valve stem is again screwed into the screw-threaded portion of the recess 15, and the packing is screwed onto the valve 120 casing 10, which places the valve back in its original operative position.

Some changes may be made in the construction and arrangement of the parts of our improved device, without departing 125 from the essential features and purposes of our invention, and it is our intention to cover by our claims, any modified forms of

structure or use of mechanical equivalents, which may be reasonably included within their scope.

We claim as our invention:

- 5 1. In a device of the character described, a casing having a plurality of pivoted fingers on its lower end, said fingers being designed to grip and engage a movable valve closure member, a centering device slidably mounted upon said casing, said centering device comprising a cone-shaped member adapted to extend partially into the valve stem opening of a valve casing, vertically adjusted bars fixed to said cone-shaped member, said bars being provided adjacent to their lower ends with a set screw, whereby the set screws may be tightened to engage the valve casing and hold said centering device in position, whereby it will form a bearing for said casing when the casing is being rotated in order to grind the movable valve closure members in the valve seat.
- 20 2. In a tool for grinding valves, a casing having a plurality of fingers pivoted to its lower end, and a squared wrench engaging portion at its upper end, said fingers being designed to grip movable valve closure members, said casing being provided with opposite registering openings intermediate

of its ends, a screw-threaded rod adjustably mounted in said casing, a nut on said rod and adapted to extend through said openings, a member on the lower end of the rod adapted when vertically moved to cause the fingers to be moved outwardly for engaging movable valve closure members of various sizes, a centering device slidably mounted on said casing, and adapted to extend partially into the valve stem opening of a valve, whereby when the tool is rotated, the centering device will form a bearing for holding the tool in the same position during the operation of it.

3. In a device of the class described, a casing having adjustable means pivoted thereon designed to grip and engage movable valve closure members of various sizes, a centering device slidably mounted upon said casing and adapted to be partially received in a valve casing, said centering device including a cone-shaped member, and means mounted on said cone-shaped member, whereby it may be locked to the valve casing, the centering device forming a bearing when the casing member is rotated.

Des Moines, Iowa, January 17, 1920.

CARL GIESER.
GLENN SHAFFER.
